MULTIPLYING APPARATUS

Wilbur Allro Steward, Omaha, Nebr.

Application November 4, 1947, Serial No. 783,907

1 Claim. (Cl. 235—69)

1

This invention relates to multiplying apparatus and more particularly to such apparatus utilizing the basic principle of Napier's rods.

In the several centuries that have passed since the perfection of the multiplying apparatus known as Napier's rods, many different versions have been proposed, but in all such embodiments of which I am aware, the arrangement has been such as to tend to cause errors in the mental adding operations which are required in performance of each problem of multiplication. For the purpose of establishing uniformity of terminology and simplifying the following discussion and description, the following examples of conventional multiplying operations are set forth.

In the multiplication of the factor 347 by the factor 543, either factor may be designated as the multiplicand, and the other designated as the multiplier, and each digit of the multiplier is multiplied by each digit of the multiplicand to produce what may be termed a partial product with respect to each such digit by digit multiplication. The several partial products with respect to the multiplication of the digits of the multiplicand by one digit of the multiplier are, in longhand multiplication, mentally added or combined in proper denominational relation to produce what may be termed an intermediate product which is set down digit by digit as the operation progresses. The successive intermediate products are set down in offset denominational relation in accordance with the denominational order of the multiplier digit from which they were respectively derived, after which the several intermediate products are added to ascertain the final product.

Thus in such an example of longhand multiplication, the written figures will appear as follows:

Example A

Multiplicand or MC	347
Multiplier or MP	543
First intermediate product	1041
Second intermediate product	1388
Third intermediate product	1735

Final product 188421

In reality, however, the production of each of the intermediate products in such a longhand multiplication involves mental operations which may be at least partially represented with respect to the first of such intermediate products, as follows:

2*Example B*

Multiplicand	347
Units digit of Multiplier	3
First partial product	21
Second partial product	12
Third partial product	9

First intermediate product 1041

The basic principle of Napier's rods is of course concerned with the simplification of the performance of operations such as Example B through elimination of the mentally performed digit by digit multiplications to obtain the successive partial products, and in attaining this result in prior art devices employing this principle, individual rods have been provided for each of the digits zero and 1 to 9, and each rod has carried the several partial products of each significant digit times the digit to which such rod is allocated.

These partial products on the several rods have of course been arranged in predetermined positions or spaces on the rods, and the right and left hand digits of each such partial product have been disposed in a particular relation in the space so that when the rods pertaining to the several digits of a multiplicand were placed in a side by side relation, the partial products relating to any selected multiplier digit would be closely related and could be added so as to determine the related intermediate product. Such rods have in the prior art been arranged in some instances to be disposed vertically in a side by side relation, and in other instances to be disposed horizontally in a side by side relation, but in every instance the disposal of the digits of the partial products on such rods has been such as to complicate the addition thereof in ascertaining the intermediate products. It is therefore the primary object of the present invention to simplify the use of partial product tables particularly in the form of rods of the aforesaid general character, and an object related to the foregoing is to enable such rods selected according to the digits of a multiplicand to be so arranged as to enable rapid and accurate summation of the partial products to be effected.

A further object is to enable the digits of the partial products that are to be added to produce the digits of any order of an intermediate to be disposed in a vertical column, thereby to make the adding operations conform more nearly to ordinary adding operations.

Other and related objects of the present invention are to simplify the relative positioning of groups of rods pertaining to a selected multiplicand; to afford a holder which not only positions and retains the rods while in use but which also affords readily accessible storage spaces for the rods that are not in use; to afford means for denominational offsetting the partial products on the adjacent rods according to the orders of the multiplicand to which such rods respectively pertain; and to afford guide or directing means of a simple character to aid in accurately selecting the partial products pertaining to a particular multiplier digit.

Other and further objects of the present invention will be apparent from the following description and claim and are illustrated in the accompanying drawings which, by way of illustration, show preferred embodiments and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claim.

In the drawings:

Fig. 1 is a plan view of a multiplying apparatus embodying the features of the invention;

Fig. 2 is a fragmentary vertical sectional view taken along the line 2—2 of Fig. 1;

Figs. 3 and 4 are left hand and right hand end views respectively of the apparatus shown in Fig. 1;

Figs. 5 and 5A are developed and diagrammatic end views respectively of one of the partial product rods;

Figs. 6 and 6A are developed and diagrammatic end views of another partial product rod;

Figs. 7 and 7A are developed and diagrammatic end views of another partial product rod;

Fig. 8 is a plan view of another form of multiplying apparatus having a large and more convenient rod storage arrangement;

Fig. 9 is a fragmentary sectional view taken along the line 9—9 of Fig. 8;

Fig. 10 is a right hand side view of the structure shown in Fig. 8;

Fig. 11 is a view showing the alternative form of partial product rods;

Fig. 12 is a left hand end view of the structure shown in Fig. 11; and

Fig. 13 is a sectional view taken along the line 13—13 of Fig. 11.

For purposes of disclosure, the invention has been illustrated in Figs. 1 to 4 as embodied in a multiplying apparatus 100 having a carrier 101 adapted not only for storage of a plurality of partial product rods 102, but also for mounting of selected of such rods 102 on an accessible upper face thereof for the determination of intermediate products of any selected multiplicand factor. The rods 102 as shown in Figs. 1 to 4 are square in cross section, and the carrier 101 is adapted for cooperation with rods of this form. The carrier 101 is generally rectangular in outline and is relatively thick so that its front face 103 is spaced substantially from its back face 104, thereby to afford space for storage openings 105 that are extended into the body of the carrier from opposite ends thereof. In this connection it will be observed that the rods 102 are somewhat longer than the carrier 101, and the storage openings 105 opening through one end face of the carrier

101 terminate, as at 105E, just short of the other end. Thus the rods 102 project at one end from the carrier 101 so as to be readily accessible for withdrawal as required. The several storage openings 105 open alternately through opposite ends of the carrier 101 so that alternate groups of rods 102 project from opposite ends of the carrier as will be evident in Fig. 1 of the drawings.

The front face 103 of the carrier 101 serves as a mounting surface for those rods 102 that are selected to represent the various digits of a multiplicand factor, and the arrangement is such that the selected rods 102 are disposed on the face 103 in parallel relation with the rods displaced denominational endwise with respect to each other in accordance with the order of the multiplicand digits that they respectively represent. Thus, in Fig. 1, rods 102 that carry the various partial products of the digits 3, 4 and 7 have been illustrated in positions representing the multiplicand factor 347, and in this novel arrangement the several partial products related to the various multiplier digits are disposed in a relationship which simplifies the addition of the digits thereof to ascertain the intermediate product of the selected multiplicand factor 347 times any selected multiplier digit. Thus the 3-rod which relates in this instance to the highest order of the multiplicand is disposed parallel to and against an upper abutment ledge 110 that is formed in an upstanding relation as a border along the upper edge of the front face 103 of the carrier 101, and the left hand end of the 3-rod is positioned in abutment with a positioning shoulder H formed in an upstanding relation at the left hand end of the face 103.

The shoulder H is the upper one of a series of such shoulder H, H—1 to H—9 which step down to the right as shown in Fig. 1 so that the last shoulder H—9 is disposed just above a lower abutment ledge 112 which extends as an upstanding border along the lower edge of the face 103. Between the ledges 110 and 112, space is afforded for mounting of ten partial product rods 102, so that the carrier, as shown, has a capacity which enables ten-order multiplicand factor. The height of the individual shoulder H to H—9 is equal to the width of the rods 102, and the horizontal spacing of the shoulders H to H—9 is related under the present invention to the spacing or disposition of the digits of the partial products on the rods 102 as will hereinafter be pointed out in the description of the specific structure of the rods, and at that time the character and advantageous relation of the index and guide markings associated with the face 103, the ledges 110 and 112 and the rods 102 will be described. With further reference however to the physical structure of the carrier 101, it will be observed that retaining or holding means are afforded on the carrier which serve to hold any selected number of rods 102 in position on the face 103. Thus a hook 115 is adapted to engage the lower edge of the lowermost rod 102 on the face 103, near the right hand end of the face 103, and a cord 116 connected to the hook 115 extends upwardly about a guide pulley 117 that is fastened to the upper right hand corner of the ledge 110 by a bracket 117B. The cord 116 then extends along the ledge 110 to a guide pulley 118 that is secured by a bracket 118B to the upper left hand corner of the ledge 110. From the pulley 118 the cord extends along the left hand end of the carrier 101 to a guide pulley 119 mounted on a bracket 119B, and the end of the cord is led about the

pulley 119 and to the left and into a bore 120 formed in the left end of the carrier 101. Within the bore 120 the cord 116 is attached to one end of a spring 121 that has its other end anchored near the right hand end of the bore 120, and thus the cord 116 is yieldingly urged so that the hook 116 holds the selected rods 102 in position. In this connection it will be observed that any tendency of the rods 102 to pivot about the right hand end of the ledge 110 is prevented by the engagement of the left ends of the rods against the upper faces of the stepped shoulders H.

While a rod 102 might be used to carry the partial products relating to a single multiplicand digit, the use of rods of square cross section affords four elongated side faces on each rod which may advantageously be utilized so as to provide the partial products of four different multiplicand digits on each such rod. Thus in Figs. 5, 6 and 7, the developed surfaces of three different classes of rods 102 have been shown whereby the capacity of the apparatus may be rendered relatively large without requiring an unduly large number of rods 102. As shown in Figs. 5 and 5A, a class I rod may have the partial products of the multiplicand digits 1, 2, 3 and 4 formed on the respective side faces thereof in the relation shown in Fig. 5A, and digital identification of the several partial product tables is afforded by identifying digits 125 disposed on the respective faces of the rod at the right hand ends of such faces.

In forming the figures of the respective partial products of a digit on a side surface of a rod, such elongated side surface is divided into a plurality of equal areas or spaces each of which may be termed a character space, and certain of which are utilized to receive individual digits of each partial product, while certain of the spaces serve as separating and guiding areas disposed between the adjacent digits of adjacent partial products. Thus, a plurality of transverse lines 127 are formed across each side surface upon which partial products are to be formed, these lines being equally spaced in an amount equal to the lateral dimension of the side surface, thereby to form a series of square spaces or areas. The left hand end space in each such side surface is allocated to the multiplier digit 1, as indicated by the designation MP-1 in Fig. 5, and the multiplicand digit to which the surface is allocated is formed therein so that the base of the figure is adjacent and parallel to the lower side edge of such elongated side surface. The next space to the right, and every third space thereafter, constitute separating spaces 129, and guide lines 130 are formed diagonally across such spaces so as to extend from the upper left corner to the lower right corner, and this slope is coordinated as will hereinafter be described with the direction and slope afforded by the stepped series of shoulders H to H-9.

The successive pairs of spaces afforded from left to right between the separating areas 129 are allocated in succession to the multiplier digits 2 to 9, as indicated by the notations MP-2 to MP-9 in Fig. 5, and the digits of the corresponding partial products are disposed in such pairs of spaces in a manner that is related to the disposition of the multiplicand digit in the most left hand space. Thus the left and right hand spaces of each such pair are allocated respectively to the right and left hand digits of the partial products, and such digits are formed in the spaces thus allocated so that the bases of such digits or figures are disposed adjacent and

parallel to the lower edge of the elongated side surface on which they are formed.

With the partial products thus disposed in a line extended along the side surface of the rod, and with separating character spaces between adjacent digits of adjacent partial products, the arrangement of the rods pertaining to selected multiplicand digits in an endwise offset relation in the manner that is shown in Fig. 1, places the digits that are to be added in a vertical column so that the addition is accomplished in a conventional manner. This of course minimizes errors. As an example, in ascertaining the intermediate product of the multiplier digit 9 times the set-up multiplicand factor 347, the units order of the intermediate product may be read off and set down as 3; the figures 6 and 6 disposed one above the other may be read off and added to obtain 12, the right hand digit 2 of which is set down as the tens digit of the intermediate product; the carry-over digit 1 may then be added to the 7 and 3 digits appearing in the next column to obtain 11, the right hand digit 1 of which is set down in the hundreds order of the intermediate product; and the carry-over digit 1 is then added to the 2 appearing in the next column to the left to ascertain the digit 3 which is set down in the thousands order of the intermediate product.

Such selection of the digits that are to be added in determining the intermediate product pertaining to a selected multiplier digit is facilitated by the guide lines 130, which as shown in Fig. 1, form continuous angular guide lines across the group of rods 102 between the partial products relating to the respective multiplier digits, and such guide lines are extended downwardly beyond the selected or set-up rods 102 by angular lines 130A formed on the face 103 of the carrier. At the upper and lower ends of the guide lines 130A, vertical lines 130B and 130C are formed across the faces of the respective ledges 110 and 112. The lines 130, 130A and 130B thus afford angular columns within which the partial products relating to the respective multiplier digits are disposed, and these columns are designated by corresponding digits 135 formed in such columns on the ledges 110 and 112 and on the face 103 at spaced points between such ledges. As an additional aid in selecting the proper partial products, the digits pertaining to alternate partial products on each rod 102 may be so formed as to have a contrasting appearance, and this may be done by use of different colors, or as herein shown, by use of light and dark or heavy and light figures in alternate partial products. Thus as shown in Fig. 1, the partial products relating to the odd multiplier digits are in heavy type, while the partial products relating to the even multiplier digits are in light type.

In the form herein illustrated, the guide lines 130 are arranged to slope downwardly from left to right, and this direction of slope is related to the direction of slope of the stepped shoulders H to H-9, and to the order in which the rods pertaining to the respective orders of the multiplicand are disposed on the face 103 of the carrier. Thus, in the form illustrated the rod 102 pertaining to the highest order of the multiplicand is arranged in the uppermost position, and the rods pertaining to the successively lower orders of the multiplicand are arranged successively below the upper rod. The principles of the present invention may, of course, be applied to a reversal of this arrangement, and in such an in-

stance the slope of the guide lines 130 and the stepped shoulders H to H-9 would be downwardly from right to left; and such shoulders in any instance may be disposed for cooperation with either of the ends of the rods 102.

In Figs. 8 to 10 of the drawings an alternative embodiment of the invention is illustrated wherein selection of the rods pertaining to a particular multiplicand is facilitated. In this embodiment, a carrier 201 is provided that is similar to the carrier 101 but without the holding means such as the hook 115, and this carrier 201 has provision for storage of a plurality of rods 102 in storage spaces 205. Extended from the lower edge of the carrier 201 is a supplemental carrier 250 that is held in place by side bars 251 and 252 that are secured by screws 253 to the sides of the carrier 250 and the ends of the carrier 201. In the upper face of the supplemental carrier 250, a plurality of spaced horizontal grooves 255 are formed so as to be adapted to receive individual rods 102. The left hand ends of the grooves 255 are closed by the side bar 251, while the side bar 252 is of less height so that the right hand end of the grooves 255 are open. The grooves 255 are twelve in number as illustrated in Figs. 8 to 10, so that three zero rods and rods pertaining to the digits 1 to 9 may be disposed respectively in such grooves for rapid selection.

In Figs. 11 to 13 another embodiment of the invention is illustrated wherein the carrier is eliminated and the rods are so formed as to embody positioning means for determining the longitudinal offset of the selected group of partial product rods. Thus as will be evident in Fig. 11, partial product rods 302 are formed with a partial product table pertaining to one selected multiplicand digit formed on one side surface thereof in the manner explained hereinabove, and at the left hand end of each rod, a downward lateral arm 360 is provided which affords an abutment against which the left end of another rod may bear. The arm 360 is so formed that the longitudinal offset of the rods will be equal to one character space, that is, the same as in the embodiment of Fig. 1. As a guide to aid in selection of the proper group of partial products, a guide rod 301 is provided which has an arm 360A at its left end in the same relation as the arms 360, and guide lines 330B, and identification digits 335 are afforded on the guide rod 301 for cooperation with the angular guide lines 130 of the rods 302.

It will be evident that within the purview of the present invention the partial product rods may be of different cross sectional forms, and that partial product tables embodying the features of the invention may be utilized in different relationships. It will also be apparent that under the present invention the arrangement of the partial product tables enables the broad prin-

ciples of Napier's rods to be utilized in such a way as to simplify multiplying operations and minimize errors in addition of the partial products.

Thus, while I have illustrated and described the preferred embodiments of my invention, it is to be understood that these are capable of variation and modification and I therefore do not wish to be limited to the precise details set forth, but desire to avail myself of such changes and alterations as fall within the purview of the following claim.

I claim:

In a multiplying apparatus operating according to the broad principle of Napier's rods, a plurality of elongated rods allocated to the respective significant digits and zero and each having an elongated side surface and having transverse lines extended across said side surface at equal intervals throughout a substantial portion of the length of said side surface to divide said side surface into a series of spaces each having a predetermined dimension longitudinally of said surface, every third one of said spaces constituting a separating space and having an angular guide line extended diagonally thereacross from one upper corner thereof to the opposite lower corner thereof, and the other spaces constituting partial product receiving spaces, all of said other spaces except one being arranged in pairs and being allocated in succession to the successive digits from 1 to 9, the spaces of such pairs constituting left and right hand spaces adapted to respectively receive the left and right digits of a partial product, each such divided side surface having the figures of the partial products of the digit to which the rod is allocated times the several digits from 1 to 9 formed thereon in said pairs of spaces in accordance with the digit to which such spaces are allocated and having said figures disposed in a line such that the bases of such figures are adjacent and parallel to the lower edge of the side surface on which they are formed, and the right and left hand digits of such figures being disposed in the related right and left hand spaces in each instance.

WILBUR ALLRO STEWARD.
